UNITED STATES PATENT OFFICE

CLARENCE R. PENNEY, OF DES MOINES, IOWA

MANUALLY OPERATED STAMP CUTTING, AFFIXING, INKING, AND CANCELING MACHINE

Application filed May 31, 1930. Serial No. 458,864.

The principal object of this invention is to provide a machine that will affix a stamp such as a revenue or tax stamp on an object such as a cigarette package or like and after affixing the stamp will cancel the same in the same operation.

A further object of my invention is to provide a repeating manually operated stamp cutting, affixing, inking and canceling machine that is easily and quickly refilled with an additional supply of stamps.

A still further object of this invention is to provide a stamp cutting, moistening and affixing machine that is manually operated with a minimum of effort.

A still further object of my invention is to provide a manually operated stamp moistening, cutting, affixing, inking and stamp canceling machine that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

39. Fig. 1 is a side view of my invention with one of the side plates removed to show its interior construction.

Fig. 2 is a longitudinal sectional view of the operating handle portion of the invention.

35. Fig. 3 is a bottom plan view of the resilient canceling pad.

Fig. 4 is a cross sectional view of the water receptacle and wick for moistening the stamps.

40. Fig. 5 is a front sectional view of the invention taken on line 5—5 of Fig. 1, and more fully illustrates the interior construction of the invention.

Fig. 6 is a side view of the housing portion 45 of the invention.

Although I shall describe my invention as particularly adapted to the affixing of tax stamps to packages of cigarettes, it may be used for many other and various purposes.

50. Many of the States of the United States of

America have a State tax on packages of cigarettes. This tax is in the form of a stamp and at present must be moistened and pasted on each package by hand labor. After the stamp is affixed to the package it must be canceled by a rubber stamp. All this procedure requires much valuable time and effort and, therefore highly undesirable. I have overcome this by providing my new stamp affixing and canceling machine.

I have used the numeral 10 to designate the housing portion of the invention. This housing has a rectangular opening 11 in its bottom and an opening 12 in its rear upper end portion, the purposes of which will herein-after be appreciated. Slidably mounted in the top of the housing 10 and directly above the rectangular opening 11 is the hollow rod 13. Secured on the lower end of this rod 13 and in the housing 10 is a spade portion 14 having teeth 15 on its lower end as shown in Fig. 5. Between the upper portion of this spade 14, the top of the housing 10 and embracing the hollow rod is a small coiled bumper spring 16 for yieldingly holding the spade a slight distance from the top of the housing when the same is in an upward position. Slidably mounted inside the hollow rod 13 is the hollow stem 17. Secured on the lower end of the hollow stem 17 is a rectangular container 18 having its forward side open as shown in Fig. 2. This container communicates with the inside of the stem 17 and has its forward open end enclosed by absorbent material 19 such as felt or the like. It should here be noted that the depth of the container 18 is much less than the length of the spade 14. The numeral 20 designates a bar secured by suitable means on the back of the container 18 and has its two ends extending into and through a vertical guide slot 21 in each of the two sides of the housing 10, respectively.

I have used the numeral 22 to designate ears formed on the spade portion 14 which are bent over and around the upper marginal edge of the bar 20 as shown in Fig. 5. By this construction when either the rod 13 or stem 17 is pushed downwardly, the bar 20

moving in the slots 21 will hold the same from any lateral movement.

Secured by the set screw 23 to the upper end of the hollow stem 17 is the knob 24 to facilitate the manual reciprocation of the operating rod and stem. The numeral 25 designates a passageway in the top of the knob 24 to the inside of the hollow stem 17. By this arrangement suitable ink 26 may be injected 10 into the passageway 25 and it will find its way to the container 18 through the hollow stem 17. This ink 26 in the container will keep the absorbent material 19 well saturated and will eliminate frequent attention from the operator. The numeral 27 designates a coiled spring embracing the rod 13, having one end 15 engaging the top of the housing 10 and its other end engaging the knob 24. The numeral 28 designates a second coiled spring 20 which embraces the stem 17, having one end engaging the top of the rod 13 and its other end engaging the knob 24. The spring 27 25 yieldingly holds the knob 24 and rod 13 in an elevated position relative to the housing 10 and the spring 28 yieldingly holds the knob 24 and stem 17 in an elevated position relative to the rod 13. By the stem 17 being yieldingly held in an elevated position relative to the rod 13, the container 18 will yieldingly 30 be held in an elevated position relative to the spade 14. When the knob 24 is manually depressed the spring 27 will first be compressed and the stem 17 and rod 13 will move downwardly together but after the spade 14 has 35 reached its limit of downward descent the coiled spring 28 and coiled spring 27 will be further compressed and the stem 17 will proceed to move further downwardly before it reaches its limit of descent. Upon releasing 40 the downward pressure on the knob 24 the coiled springs 27 and 28 will return the above described handle or knob assembly to a position shown in Fig. 1.

It should be noted that the two sides of the 45 container 18 extend some distance below the bottom of the container. Pivoted to the rear and lower portion of each of the two sides of the container is the trough member 29. This trough member, as will be noted, embraces the two sides of the container and its forward end may move toward or away from the bottom of the container. The distance of travel of the same away from the container is limited by a projection 30 on each side 50 of the container extending into a slot 31 in each side of the trough as shown in Fig. 1. The numeral 32 designates a small spring for holding the forward end of the trough its limit of distance away from the bottom 55 of the container. Secured on the bottom of the trough 29 is a resilient stamp pad 33 which may possess any desirable indicia such as the word "Cancelled" and the numeral assigned to the user of the machine. The 60 numeral 34 designates a projection formed

inside the housing 10 and on its forward end. Pivoted to this projection are the two arms 35 carrying the roller 36 in their free ends. The numeral 37 designates a small spring for 70 yieldingly holding the arms 35 in an elevated condition. By this arrangement when the knob 24 is forced downwardly the roller 36 will move, by its swinging action, across the resilient stamp pad 33 to the side of the container 18 and onto the absorbent material 19 from which it will become affected with ink. When the knob 24 is permitted to move upwardly the roller 36 will move from the absorbent material 19 to and across the pad 33, thereby properly inking the same. In each side of the housing 10, extending 75 forwardly and downwardly from its upper rear end is a slot 38 as shown in Fig. 6, capable of being manually slid either out of these two slots 38 or to the bottom of the same is a shaft 39 designated to carry the usual roll 40 of stamps having a line of perforations between each individual stamp.

Slidably mounted in the lower rear end of the housing 10 is the water receptacle 41 designed to contain water 42 or the like. In the upper and forward end portion of this receptacle is a horizontal slot opening 43 through which two strips 44 of absorbent material such as felt or the like is designed to protrude as illustrated in Fig. 4 and Fig. 5. The upper end of these strips are held in a near horizontal position by projections 45 formed on the receptacle and adjacent the lower marginal edge of the opening 43. This receptacle may be replenished with water by removing the cork 46 which encloses a filling port. Pivoted on the forward end of the receptacle 41 and normally extending forwardly to a position under the trough 29 is the finger 47. This finger is normally held in this position as shown in Fig. 1, by the small coiled spring 48 and is designed to engage and hold the underside of the forward end of the stamp roll 40. The numeral 49 designates a leaf spring secured to the housing 10 as shown in Fig. 1 and designed to engage the upper side of the free end portion of the stamp roll 40.

By this construction when the knob 24 is depressed the teeth 15 of the spade 14 will descend and catch the first row of perforations between the first and second stamp and carry the same downwardly with it. The distance of downward travel of this spade will just equal the length of the next stamp which will be unreeled from the roll 40. This unreeeling of an additional stamp from the roll 40 by the spade 14 will cause the same to have 115 its lower side engage the strip 44, thereby moistening the glue on the same. When the spade 14 passes the row of teeth 50, the first stamp will be severed from its roll of gummed stamps and it will be engaged on its up- 120

per surface by the rubber stamp 33 on the trough 29.

As we have seen after the spade reaches its limit of downward movement the stem 17 5 will continue to move downwardly and carry with it the trough 29. This depressing action on the stamp as the container 18 continues to move downwardly will be somewhat of a yielding nature, due to the trough being held 10 its limit of distance away from the container 18 by the spring 32. As soon as the forward end of the trough 29 holding the stamp pad 33 reaches its limit of downward movement by bringing the forward end of the stamp in 15 contact with the package or container to which the stamp is to be affixed, the container 18 will continue to move downwardly in the trough and will cause the rear end of the trough to eventually move downwardly until 20 it reaches a horizontal plane, thereby not only aiding in the cutting of the stamp from the roll if the same has not already been completely cut by the spade 14 but successfully and progressively laying the gummed stamp 25 onto the package from a point forward to a point to the rear. As the stamp was moist when it passed the strips 44 and as it was forced onto the package with considerable force it will be securely affixed to the same. 30 By the stamp pad 33 being suitably inked, it will cancel the affixed stamp by its force upon the top of the same during the affixing action. When the spade 14 moves downwardly the finger 47 also moves downwardly by engagement with the same and travels to an inoperative position as shown by dotted lines in Fig. 1. When the knob 24 is released or the device is lifted from the package to which a stamp 35 was just affixed, the spade 14 will be moved up into the housing 10, and the inking roller 36 will move across the stamp 33 as we have seen.

As the spade 14 moves upwardly the finger 45 47 will also move to a near horizontal position as shown in Fig. 1 and will hold the next individual stamp in a proper position for the teeth of the spade 14 to engage the perforations between that stamp and the second stamp for the next operation.

The numeral 51 designates a lid for enclosing the opening 12 and also for engaging the receptacle 41. When the roll of stamps 40 is depleted the lid 51 is raised and the shaft 55 39 removed from the slots 38 and a new roll of gummed stamps placed on the shaft 39 and replaced in the machine. From the foregoing description it will readily be seen that I have provided a repeating manually operated 60 stamp cutting, affixing, moistening, inking and canceling machine as is easily operated by merely placing the opening 11 over and upon the package to which the stamp is to be affixed and pushing downwardly on the knob 24. Naturally each time the knob 24 is forced

downwardly a stamp will be cancelled and affixed to a package.

Some changes may be made in the construction and arrangement of my improved manually operated stamp cutting, affixing, inking and canceling machine, without departing from the real spirit and purpose of my invention, and it is my intention to cover by my claims any modified forms of structure or use of mechanical equivalents which may be reasonably included within their scope.

I claim:

1. In a device of the class described, a housing designed to contain a roll of flexible material; said material being gummed on one of its sides, a delivery port in the bottom of said housing, absorbent material designed to be moistened and capable of engaging the gummed side of said flexible material as it is unwound, a rod slidably mounted in said housing, a spade member in said housing and secured to said rod capable of cutting off a portion of said flexible material each time said rod is reciprocated, a member operatively secured to said rod capable of engaging the cut-off portion of said flexible material and delivering it through said port, and a flexible canceling pad secured to said member operatively secured to said rod capable of engaging the upper side of said piece of flexible material when the same is delivered through said port.

2. In a device of the class described, a housing having an outlet port, a rotatable shaft in said housing designed to support a roll of gummed stamps, a rod slidably mounted in the top of said housing and above said port, a spade member secured to said rod capable of engaging the perforations between the first and second stamp and the cutting of said first stamp from said second stamp when the same reaches the limit of its downward movement, a trough member operatively pivoted at its rear end portions to said rod, a means for limiting the movement of its forward end portions away from said rod, and a yielding means for holding said trough member its limit of distance away from said rod.

3. In a device of the class described, a housing having an outlet port, a rotatable shaft in said housing designed to support a roll of gummed stamps, a rod slidably mounted in the top of said housing and above said port, a spade member secured to said rod capable of engaging the perforations between the first and second stamp and the cutting of said first stamp from said second stamp when the same reaches the limit of its downward movement, a container secured to said rod, a canceling pad operatively connected to the bottom of said container designed to engage the top of said stamp that is cut off, force the same through the said port onto an object and cancel it, absorbent material in

one side of said container and communicating with the inside of said container, and an inking roller capable of running across said canceling pad and onto said absorbent material when said rod is pushed downwardly in said housing and capable of returning from said absorbent material and across said canceling pad when said rod returns to an upward position relative to said housing.

10 4. In a device of the class described, a housing having an outlet port, a rotatable shaft in said housing designed to support a roll of gummed stamps, a rod slidably mounted in the top of said housing and above said port, a spade member secured to said rod capable of engaging the perforations between the first and second stamp and the cutting of said first stamp from said second stamp when the same reaches the limit of its downward movement, an engaging member operatively connected to said rod capable of forcing the cut off stamp through said port, a finger pivoted in said housing for holding the end of said roll of stamps in proper position

15 20 25 for the said spade to engage the next roll of perforations each time said rod is reciprocated in said housing, and a yielding means for holding said finger in a normal operative position.

30 position.

5. In a device of the class described, a housing having an outlet port, a rotatable shaft in said housing designed to support a roll of gummed stamps, a rod slidably mounted in the top of said housing and above said port, a spade member secured to said rod capable of engaging the perforations between the first and second stamp and the cutting of said first stamp from said second stamp when the same reaches the limit of its downward movement, an engaging member operatively connected to said rod capable of forcing the cut off stamp through said port, a finger pivoted in said housing for holding the end of said roll of stamps in proper position for the said spade to engage the next roll of perforations each time said rod is precipitated in said housing, a yielding means for holding said finger in a normal operative position, and a leaf spring for preventing the stamps unwound from said roll from accidentally becoming rewound upon the main roll.

6. In a device of the class described, a housing having a delivery port and designed to contain a roll of gummed stamps, a hollow rod slidably mounted in the top of said housing and above said port, a spade member secured to said rod, for engaging the end stamp of said roll each time said rod is reciprocated, unwinding an additional stamp from said roll and cutting off said first stamp, a hollow stem slidably mounted in said rod, a container on the end of said stem and adjacent said spade, a knob on the other end of said stamp, a coiled spring between said knob

and the end of said rod, a coiled spring between said knob and said housing, a coiled spring between said spade and the top of said housing, a passageway in said knob leading from the outside atmosphere to the inside of the stem, absorbent material enclosing one side of said container, a canceling stamp pad operatively connected to the bottom of said container, and an inking roller capable of passing over both pad and absorbent material when said rod and stamp are reciprocated by manually operating said knob.

7. In a device of the class described, a housing having a delivery port and designed to contain a roll of gummed stamps, a hollow rod slidably mounted in the top of said housing and above said port, a spade member secured to said rod, for engaging the end stamp of said roll each time said rod is reciprocated, unwinding an additional stamp from said roll and cutting off said first stamp, a hollow stem slidably mounted in said rod, a container on the end of said stem and adjacent said spade, a knob on the other end of said stamp, a coiled spring between said knob and the end of said rod, a coiled spring between said knob and said housing, a coiled spring between said spade and the top of said housing, a passageway in said knob leading from the outside atmosphere to the inside of the stem, absorbent material enclosing one side of said container, a canceling stamp pad operatively connected to the bottom of said container, an inking roller capable of passing over both pad and absorbent material when said rod and stamp are reciprocated by manually operating said knob, a slot in each side of said housing, a bar secured to said container and capable of sliding in said slots when said rod and stem are reciprocated, and ears formed on said spade capable of engaging said bar.

CLARENCE R. PENNEY.
